DESIGN FOR A WASHING MACHINE

Isaac Newton Merritt, Oak Park, Ill., assignor to
Electric Household Utilities Corporation, Chi-
cago, Ill., a corporation of Illinois

Application October 4, 1940, Serial No. 95,627

Term of patent 14 years

To all whom it may concern:

Be it known that I, Isaac Newton Merritt, a citizen of the United States, residing at Oak Park, in the county of Cook and State of Illinois, have invented a new, original, and ornamental Design for a Washing Machine, of which the following is a specification, reference being had to the accompanying drawings, forming a part thereof.

In the drawings:

Fig. 1 is a front elevational view of a washing machine showing my new design.

Fig. 2 is a top plan view thereof; and

Fig. 3 is a side elevational view thereof.

I claim:

The ornamental design for a washing machine, substantially as shown.

ISAAC NEWTON MERRITT.
